[57] CLAIM

The ornamental design for a dispensing system, as shown and described.

DESCRIPTION

FIG. 1 is a front elevation view of a dispensing system showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view shown with the sprayer removed from the recess;

FIG. 8 is a right side elevation view thereof;

FIG. 9 is a top plan view thereof;

FIG. 10 is an enlarged rear elevation view of the sprayer removed for clarity of illustration; and,

FIG. 11 is a bottom plan view thereof.
